RAILWAY SIGNALING SYSTEM

Ralph R. Kemmerer, Swissvale, Pa., assignor to
The Union Switch & Signal Company, Swiss-
vale, Pa., a corporation of Pennsylvania

Application July 31, 1940, Serial No. 348,937

16 Claims. (Cl. 246—38)

My invention relates to a railway signaling system of the type employing coded or periodically interrupted energy in the track circuits thereof.

It is an object of my invention to provide an improved form of signaling system of the type described having cab signals to indicate traffic conditions in the track stretch, and being without wayside signals except a marker at the entrance of each track section which is lighted when 5 the section is occupied to indicate to following trains the entrance to an occupied section.

A further object of my invention is to provide a signaling system of the type described and incorporating means to check the integrity 15 of the lamps of the markers and controlling the supply of energy to the sections in the rear so that if while a section is occupied the lamp of the marker for that section is defective, energy effective to produce a proceed indication on the 20 locomotive of a following train will not be supplied to the rails of the adjacent section in the rear.

Another object of my invention is to provide an improved coded signaling system employing 25 wayside signals, and having lightout protection means arranged so that in the event a signal lamp is defective, the signal will be conditioned to display its next most restrictive indication, while the energy supplied to the section in the 30 rear will be changed so as to be commensurate with the indication displayed by the signal.

A further object of my invention is to provide a railroad signaling system having wayside signals controlled by coded track circuit apparatus, 35 the signals being normally dark and being lighted on the approach of a train, the equipment being arranged so that if the lamp of a signal is defective, the coded energy supplied to the adjacent section in the rear will be altered so that a 40 train in the section in the rear of the defective signal will receive a more restrictive indication than it normally would.

Other objects of my invention and features of novelty will be apparent from the following 45 description taken in connection with the accompanying drawings.

I shall describe three systems embodying my invention, and shall then point out the novel features thereof in claims.

In the drawings Fig. 1 is a diagram showing 50 a signaling system having a marker lamp at the entrance to each block and incorporating lightout protection means provided by my invention, and

Figs. 2 and 3 are diagrams showing wayside

signaling systems employing lightout protection means provided by this invention.

Referring to Fig. 1 of the drawings, there is shown therein a stretch of railway track having track rails 1 and 2 over which traffic moves 5 in the direction indicated by the arrow, and which are divided by insulated joints 3 into the usual track sections. Two complete sections are shown and are here designated 11T and 12T.

The track stretch shown in Fig. 1 employs cab 10 signals on the locomotives traversing the track stretch, and does not have wayside signals except for a marker M at the entrance to each block or track section.

The signaling system shown in Fig. 1 is of 15 the three-indication variety and makes use of energy coded at two different code frequencies. This coded energy is provided by code transmitters CT having two circuit making and breaking contacts 75 and 180 which are operated at 20 different speeds by a motor or other means so as to provide 75 or 180 energy impulses per minute which are separated by periods of equal duration during which no energy is supplied.

The system shown employs coded alternating 25 current in the track circuits. This current may be supplied from any suitable source and may be distributed throughout the track stretch by a transmission line, not shown, the terminals of the source being designated BX and CX. 30

The cab signal apparatus adapted to be used in connection with the wayside apparatus is not a part of this invention and any form of equipment well known in the art may be employed. One form of apparatus which may be employed is 35 shown in Letters Patent of the United States No. 1,986,679 issued January 1, 1935, to Lloyd V. Lewis.

Each of the track sections has a code following 40 track relay TR at the entrance end of the section and receiving energy over the section rails through a rectifier RX. Each of the track relays has associated therewith code detecting means comprising a transformer DT and a slow 45 releasing relay H, while each marker lamp M has associated therewith a lightout relay LOR.

The equipment is shown in the condition which it assumes when section 12T and the sections in advance are vacant. At this time energy of 180 50 code frequency is supplied through the track transformer 11TT to the rails of section 11T by the means associated with the adjacent section in advance. The equipment associated with the section in advance operates in the same manner 55

as that associated with section 11T, as herein-after explained in detail.

The energy supplied to the rails of section 11T feeds through the rectifier 11RX to the track relay 11TR and produces code following operation of this relay so that the end portions of the primary winding of the transformer 11DT are alternately energized from a local source of direct current, and current is induced in the transformer secondary winding, while a contact of the track relay rectifies the energy supplied from the transformer secondary winding to the relay 11H. The relay H is of a type which is slow to release its contacts with the result that its contacts remain picked up during the intervals between the supply of impulses of energy thereto.

As relay H is picked up, its contact 20 establishes the circuit to supply energy of 180 code frequency to the rails of the section in the rear, while contact 21 interrupts the circuit of the marker lamp 11M.

As energy of 180 code frequency is supplied to the rails of section 12T, the relay 12H is picked up and establishes the circuit to supply energy of 180 code frequency to the section farther in the rear, while the circuit of the lamp 12M is interrupted.

As energy of 180 code frequency is supplied to the rails of the section in the rear of section 12T, the cab signal apparatus, shown diagrammatically, for a locomotive in that section will operate to provide its green or clear indication.

If the locomotive advances into section 12T, the cab signal apparatus on the locomotive will respond to the energy of 180 code frequency supplied to the track rails to provide the engineer with a clear signal indication.

On entrance of the locomotive into section 12T the track relay 12TR is shunted and ceases to respond to coded energy with the result that energy is no longer supplied through the transformer 12DT to the relay 12H. On release of relay 12H contact 21 of the relay establishes the circuit of the marker lamp 12M, and if the filament of this lamp is intact so that the lamp is lighted, the lightout relay 12LOR will pick up as the winding of this relay is connected in series with the marker lamp.

On picking up of the lightout relay 12LOR the circuit for supplying energy of 75 code frequency to the section in the rear is established, and is traced from terminal BX of the source of alternating current through contact 75 of the code transmitter 12CT, front contact 23 of relay 12LOR, back contact 20 of relay 12H and primary winding of the track transformer 12TT to terminal CX.

When the train advances into section 11T, the equipment associated with this section operates in the manner explained in connection with section 12T so that energy of 75 code frequency is supplied to the rails of section 12T, while the marker lamp 11M is lighted.

As long as any portion of the train remains in section 12T, the track relay 12TR is shunted so that energy of 75 code frequency is supplied to the section in the rear, while the marker lamp 12M is lighted to indicate to a following train that section 12T is occupied.

In addition, as long as any portion of the train remains in section 12T, the track rails are shunted and coded signal control current does not flow in the rearward portions of the track rails of section 12T so that if a following train should

enter this section, the cab signal apparatus on the locomotive of the train would be conditioned to display its most restrictive or stop indication.

When the rear of the train vacates section 12T, the energy of 75 code frequency feeds to the track relay 12TR and produces code following operation of this relay with the result that energy is supplied through the transformer 12DT to the relay 12H, and contact 20 is picked up to interrupt the circuit for supplying energy of 75 code frequency to the section in the rear and to establish the circuit for supplying energy of 180 code frequency thereto. In addition, contact 21 of relay 12H is picked up so that the marker lamp 12M is extinguished, while the lightout relay 12LOR releases.

When the train vacates section 11T, the equipment associated with this section operates in the manner described in detail above to extinguish the marker lamp 11M, and to change the energy supplied to section 12T from 75 to 180 code frequency. On this change in the energy the track relay 12TR continues to respond to coded energy and the relay 12H is maintained energized to maintain the supply of energy of 180 code frequency to the section in the rear.

Operation of equipment shown in Fig. 1 if a marker lamp is defective

The equipment provided by this invention includes means to check the integrity of the filaments of the marker lamps so that if one of these lamps fails to light when it should, the energy supplied to the section in the rear will be controlled so that the cab signal apparatus on a train entering the section in the rear will not receive a proceed indication, but instead will receive the stop or most restrictive indication.

For purposes of illustration it will be assumed that a train enters section 11T and that the lamp of the marker lamp 11M is defective and fails to light.

When the train enters section 11T, the track relay 11TR is shunted and energy is no longer supplied through transformer 11DT to the relay 11H, and this relay releases so that contact 20 interrupts the circuit for supplying energy of 180 code frequency to the rails of section 12T.

In addition, contact 21 of relay 11H is released and establishes the circuit of the lamp 11M, but as it is assumed that the lamp is defective, this lamp is not lighted while the relay 11LOR is not energized and its contact 23 remains released. Accordingly, energy of 75 code frequency is not supplied to the rails of section 12T, and instead steady energy is supplied thereto over a circuit which is traced from terminal BX, over back contact 23 of relay 11LOR, back contact 20 of relay 11H, and the primary winding of transformer 12TT.

When the train under consideration vacates section 12T, this steady energy will feed to the track relay 12TR and keep it steadily energized so that energy is not supplied through the transformer 12DT to the relay 12H and this relay is released to light the lamp 12M and to effect the supply of energy of 75 code frequency to the section in the rear.

Accordingly, a second or following train will receive a restrictive indication when it enters the section in the rear of section 12T, while it will be warned by the marker lamp 12M when it reaches section 12T. If the train advances into section 12T, the cab signal equipment on the locomotive will give the most restrictive indi-

energy will no longer be supplied through the decoding transformer 14DT to the relays 14H and 14J.

On release of relay 14H contact 30 interrupts the circuit of the lamp G and establishes the circuit of the lamp R of signal 14S. The circuit of the lamp R is traced from terminal B through back contact 30 of relay 14H, winding of light-out relay 14RLO, and lamp R to terminal C. If the lamp R is not defective and becomes lighted, the relay 14RLO will be energized and its contact 35 is picked up and interrupts the circuit of the marker lamp M.

In addition, on release of the relay 14H contact 34 interrupts the circuit for supplying energy of 180 code frequency to the rails of section 15T, and establishes the circuit for supplying energy of 75 code frequency to section 15T. This circuit is traced from terminal BX through code transmitter contact 75, and back contact 34 of relay 14H to the primary winding of transformer 15TT.

As long as the train is in section 14T, the cab signal equipment on the locomotive, if the locomotive is provided with this equipment, will continue to receive energy of 180 code frequency supplied by the equipment associated with section 14T and the cab signal equipment will display its clear indication.

30 When the train advances into section 14T, the equipment associated with that section will operate as described in detail in connection with section 14T to supply energy of 75 code frequency to the rails of section 14T, and to condition the 35 signal 14S to display its red or stop indication.

When the train clears section 14T, energy of 75 code frequency feeds to the track relay 14TR and this relay operates to supply energy through the transformer 14DT to the relay 14H. As the 40 track relay is responding to energy of the 75 code frequency, too little energy is supplied through the resonant unit 14RU to pick up the relay 14J.

On picking up of relay 14H contact 30 interrupts the circuit traced above for lighting the red lamp R and establishes the circuit of the yellow or caution lamp Y of signal 14S. This circuit is traced from terminal B over front contact 30 of relay 14H, back contact 31 of relay 14J, winding of lightout relay 14YLO, and lamp Y to terminal C. If the lamp Y lights as it should, the relay 14YLO will be picked up so that the circuit for supplying energy of 180 code frequency to the section in the rear is established. 55 This circuit is traced from terminal BX over contact 30 of the code transmitter, front contact 32 of relay 14YLO, back contact 33 of relay 14GLO, and front contact 34 of relay 14H to the transformer 15TT.

60 When the train vacates section 14T, the track relay for this section responds to energy of 75 code frequency, while the energy supplied to section 14T is changed to 180 code frequency. On this change in the frequency of the energy supplied to section 14T the track relay 15TR operates at a higher speed and sufficient energy is supplied through the resonant unit 14RU to pick up the relay 14J.

When relay 14J picks up, its contact 31 interrupts the circuit of the yellow lamp Y and of the relay 14YLO, and establishes the circuit of the green lamp G and of the relay 14GLO. On picking up of the relay 14GLO its contact 33 interrupts the circuit traced above for supplying energy of 180 code frequency to section 15T, and

establishes a connection shunting the contact 36 of the relay 14YLO so that energy of 180 code frequency continues to be supplied to section 15T.

Operation of system shown in Fig. 2 in the event 5 a signal lamp is defective

The system provided by this invention is arranged so that if any one of the signal lamps is defective and fails to light when it should, the lamp for the next most restrictive indication will be lighted, while the energy supplied to the section in the rear is controlled so as to be consistent with the aspect displayed by the signal.

If, for example, the green lamp G of signal 14S is defective and does not become lighted when the relays 14H and 14J are picked up, the relay 14GLO will be released and its contact 38 will establish a circuit to light the yellow lamp Y. This circuit includes front contact 30 of relay 14H, back contact 33 of relay 14GLO, winding of relay 14YLO, and lamp Y. At this time the relay 14GLO is released and the relay 14YLO is picked up so that a circuit is established to supply energy of 180 code frequency to section 15T. This is the code frequency which it is proper to supply to section 15T when the signal 14S is displaying its yellow or caution indication.

The system is also arranged so that if the yellow light Y is defective and does not become lighted when it should be, the red lamp R will be lighted, while the energy supplied to the section in the rear will be changed from 180 to 75 code frequency.

The yellow lamp should be lighted when the relay 14H is picked up and the relay 14J is released, or when the relay 14H is picked up and the relay 14GLO is released. In either case the relay 14YLO will be picked up if the lamp lights, 40 but will be released if the lamp fails to light.

When the relay 14YLO is released at a time when the relay 14GLO is released, a circuit is established to light the red or stop lamp R. This circuit is traced from terminal B through back contact 39 of relay 14YLO, back contact 40 of relay 14GLO, winding of relay 14RLO, and lamp R to terminal C.

In addition, when relay 14YLO releases at a time when relay 14GLO is released and relay 14H 50 is picked up, a circuit is established to supply energy of 75 code frequency to the section in the rear. This circuit is traced from terminal BX over code transmitter contact 75, back contact 35 of relay 14YLO, back contact 33 of relay 14GLO, 55 and front contact 34 of relay 14H to the track transformer 15TT.

If the red lamp R is intact and becomes lighted, the relay 14RLO will be picked up and contact 35 will interrupt the circuit of the marker lamp M. 60

It will be seen, therefore, if for any reason the yellow light Y fails to light when it should, the red light R will be lighted instead, while the energy supplied to the section in the rear will be changed from 180 to 75 code frequency. This will 65 cause the signal for the section in the rear to change its indication from green to yellow so that a following train will receive a caution indication at the entrance to section 15T and will not approach the signal 14S at full speed at a time 70 when the signal 14S is displaying its red or stop indication.

The system is also arranged so that if the red or stop lamp R is defective and does not become lighted when it should, the marker lamp M will be 75

*Construction and operation of modification
shown in Fig. 2*

cation in response to the presence of steady uncoded energy in the rails of section 12T.

As the following train receives the most restrictive indication when it reaches section 12T, it will be moving at very slow speed when it approaches the marker lamp 11M, and failure of this lamp to be illuminated will not create a serious hazard as the train will be able to stop before striking the train present in section 11T.

When the first train vacates section 11T, the track relay 11TR responds to coded energy and relay 11H picks up to interrupt the supply of steady energy to the rails of section 12T, and to establish the circuit to supply energy of 180 code frequency to the rails of section 12T in the usual manner.

From the foregoing it will be seen that when the marker lamp of an occupied block is defective, the energy supplied to the section in the rear is controlled so that a following train will receive the most restrictive signal indication one block before it reaches the defective lamp. This insures that the following train will reduce its speed so as to be able to stop before entering the occupied block.

If the energy supplied to the rails of the section at the rear of a section having a defective marker lamp were not controlled in this manner, a following train would receive a proceed indication in the section in the rear of the defective lamp and would be traveling at a substantial speed when it approached the defective lamp, and the engineer might not see the lamp since the lamp would not be lighted as it should be. Accordingly, the engineer of the second train would not know when he reached the entrance of the occupied block and would continue on into the occupied block. After the locomotive of the second train enters the occupied block, the cab signal equipment carried by it will give the most restrictive indication.

However, if the first train stopped with the rear end thereof adjacent the entrance end of section 11T, the second or following train might not be able to stop soon enough after entering the occupied section and receiving the stop indication to avoid hitting the first train.

As the system provided by this invention provides a marker lamp to mark the entrance to an occupied block, following trains are warned when they approach an occupied section and can stop before entering the section or before reaching a train in the section.

Furthermore, the system is arranged so that if the marker lamp is not illuminated when it should be, the supply of coded energy to the section in the rear is cut off, while the marker lamp at the entrance of the section in the rear is lighted and the energy supply to the rails of that section is controlled to cause the cab signal equipment on a locomotive in the section in the rear of the defective lamp to display its most restrictive indication.

It will be seen, therefore, that the system provided by this invention provides a maximum degree of safety both when the system is functioning as intended, and when the lamp of one of the marker lamps is defective.

The means provided by this invention for controlling the supply of coded energy to the section in the rear is applicable to a signaling system employing wayside signals, and Fig. 2 is a diagram showing this application of the invention.

Referring to Fig. 2, there is shown therein a stretch of railway track employing wayside signals of the color light type. One block section, identified as section 14T, together with portions of two other sections, is shown.

Each of the track sections has at the entrance end thereof a wayside signal having a green or clear lamp G, a yellow or caution lamp Y, a red or stop lamp R, and a marker lamp M which may be of any distinctive color.

The system shown in Fig. 2 makes use of coded energy of two code frequencies in the track circuits thereof, while it has decoding means similar to the code detecting means employed in the system shown in Fig. 1.

The equipment is shown in Fig. 2 in the condition which it assumes when the track stretch is vacant. At this time energy of 180 code frequency is supplied to the rails of section 14T by the equipment associated with the adjacent section in advance, while this energy feeds through the rectifier 14RX to the track relay 14TR and produces code following operation of this relay.

As a result of code following operation of the track relay 14TR, the two end portions of the primary winding of the decoding transformer 14DT are alternately energized from a local source of direct current, not shown, and energy is induced in the secondary windings of the transformer, while a contact of the track relay rectifies the energy supplied from one of these secondary windings to the winding of relay 14H. Energy is supplied from the other secondary winding of the transformer 14DT through a resonant rectifier unit 14RU to the relay 14J.

The resonant unit RU includes a capacitor and an inductance which are arranged and proportioned so as to pass energy sufficient to operate the relay J when the track relay is responding to energy of 180 code frequency and to pass too little energy to operate the relay J when the track relay is responding to energy of a different code frequency, such as 75 code frequency. The unit RU includes a rectifier which converts into direct current the alternating current supplied through the unit.

As the track relay 14TR is responding to energy of 180 code frequency, the relays 14H and 14J are both picked up, and the green or clear lamp G of signal 14S is lighted by current supplied over the circuit which is traced from terminal B of a local source of direct current through front contact 30 of relay 14H, front contact 31 of relay 14J, winding of lightout relay 14GLO, and lamp G to terminal C.

As the relay 14H is picked up, the circuit for supplying energy of 180 code frequency to the section in the rear is established, and is traced from terminal BX of the source of alternating current signal control energy through contact 180 of code transmitter 14CT, front contact 33 of relay 14GLO, front contact 34 of relay 14H, and primary winding of track transformer 15TT to terminal CX.

As energy of 180 code frequency is supplied to the rails of section 15T, the signal, not shown, for that section is conditioned to display its green or clear indication, while the cab signal equipment of a locomotive present in section 15T will display its clear indication.

If a train moving in the normal direction of traffic, that is from left to right, enters section 14T, it will shunt the track relay 14TR and

lighted, while steady uncoded energy will be supplied to the section in the rear.

The red lamp R of signal 14S should be lighted when the relay 14H is released, or when relay 14H is picked up and relay 14YLO is released. In either case when the red lamp is lighted, relay 14RLO is picked up, but if the lamp is defective, the relay 14RLO will be released and its contact 35 will establish the circuit to light the marker lamp M, while contact 42 will establish a circuit to supply steady energy to the section in the rear.

One circuit of the marker lamp M is traced from terminal B through back contact 39 of relay 14YLO, back contact 40 of relay 14GLO, and back contact 35 of relay 14RLO to lamp M. Another circuit for the marker lamp is traced from terminal B through back contact 39 of relay 14YLO, back contact 40 of relay 14GLO, and back contact 35 of relay 14RLO and lamp M to terminal C.

The circuit for supplying steady energy to section 15TT is traced from terminal BX through back contact 42 of relay 14RLO and thence over back contact 34 of relay 14H, if this relay is released. If relay 14H is picked up, the circuit for supplying steady energy to the section in the rear is traced from terminal BX over back contact 42 of relay 14RLO, back contact 36 of relay 14YLO, back contact 33 of relay 14GLO, and front contact 34 of relay 14H. In either case the circuit for supplying energy of 75 code frequency is maintained, but the steady energy supplied over back contact 42 of relay 14RLO fills in the "off" periods in the code so that the code is ineffective.

On the supply of steady energy to the rails of section 15T the track relay for that section is steadily picked up with the result that the red-or stop lamp of the associated signal is lighted, while energy of 75 code frequency will be supplied to the section farther in the rear to condition the signal for that section to display its caution indication.

Accordingly, a following train will receive a caution indication two blocks before it reaches the signal with the defective lamp, and will receive a stop indication one block before it reaches that signal. The train, therefore, will be traveling at slow speed when it reaches the signal at which the marker lamp is lighted and the engineer will have ample time to stop before striking a train in advance of the marker lamp. The marker lamp serves to identify the signal and shows the location of the signal, and also marks the entrance to an occupied block.

From the foregoing it will be seen that the system provided by this modification of the invention is arranged to check the integrity of the lamps of the wayside signals, and that in the event one of these is defective, the lamp providing the next most restrictive indication is lighted, while the energy supplied to the section in the rear is changed to that proper for that signal indication.

This invention is applicable to track stretches having other types of wayside signals, and Fig. 3 is a diagram showing the invention applied to a signaling system employing wayside signals of the searchlight type. A signal of the type which may be employed is shown in Letters Patent of the United States No. 2,133,603, issued October 18, 1938, to Wesley B. Wells.

Construction and operation of modification shown in Fig. 3

In the system shown in Fig. 3, the lamps of the signals are normally dark, and are lighted

on entrance of a train into the section in the rear of the signal. Any desired means for approach lighting may be employed to control the circuits of the signal lamps. The means shown in the drawings is substantially the same as that shown in Letters Patent of the United States No. 2,174,255 to Herman G. Blosser.

Referring to Fig. 3 of the drawings, there is shown therein a stretch of railroad track having track rails 1 and 2 which are divided by insulated joints 3 into the customary successive track or block sections. One complete section, which is identified as section 18T, together with portions of the adjoining sections is shown.

Each of the track sections has at the entrance end thereof a wayside signal S together with a track relay and decoding means for controlling the signal, and, in addition, means for controlling the supply of coded energy to the section in the rear.

The equipment is shown in the condition which it assumes when the track stretch is vacant. At this time energy of 180 code frequency is supplied to the coding relay 17CTM in the manner hereinafter explained in connection with section 18T, and the contacts of this relay are picked up and released at this rate.

As a result of code following operation of the coding relay 17CTM impulses of master code energy are supplied from the track battery 18TB to the rails of section 18T during the picked-up periods of the relay contacts, while during the released periods of the relay contacts connection is established to permit impulses of feed back energy to be supplied from the section rails to the pick-up winding 47 of the relay 17AR, and to also establish a circuit to supply energy from the battery 18TB to the holding winding 52 of the relay 17AR and to the winding of the relay 17AP when contact 51 of relay 17AR picks up.

The master code energy supplied to the rails of section 18T feeds to the track relay 18TR and causes code following operation of this relay with the result that energy is supplied through the decoding transformer 18DT to the relay 18H and also to the impulse relay 18IR. As a result of the supply of energy to the impulse relay 18IR this relay operates to disconnect the track relay 18TR from the rails of section 18T and to supply impulses of feed back energy from the battery 18AB to the rails of section 18T during the "off" periods in the master code supplied to the rails of section 18T.

As long as the track section is vacant, therefore, the track relay 18TR responds to master code energy, while feed back energy is supplied over the section rails to the relay 17AR which energizes the slow releasing relay 17AP.

The construction and operation of this portion of the system is not a part of this invention and is described in detail in the patent to Blosser, identified above.

The relay 17AP has associated therewith a slow releasing repeater relay 17APP which is energized when the relay 17AP is picked up. The relays 17AP and 17APP together control the lamp of the signal 17S, and also control the supply of energy to the decoding unit associated with the track relay for section 18T for detecting when the relay is responding to energy of 180 code frequency. The operation of this portion of the apparatus is best understood by reference to the corresponding apparatus associated with section 18T.

As the track stretch is assumed to be vacant,

the relays 18AP and 18APP are energized in the manner explained in detail above, and the circuit for supplying energy to the primary winding of the decoding transformer 18DTA is interrupted by contact 56 of relay 18AP. Accordingly, energy is not supplied from this transformer to relay 18J and the relay 18J is released. As the circuit of the decoding transformer 18DTA is interrupted when section 19T is vacant, no energy is consumed by this transformer and the resonant rectifier unit 18RUA and there is a substantial saving of current for this reason. As long as section 19T is vacant, the signal 18S is dark and there is no need to energize the relay 18J.

At this time the circuit of the lightout relay 18LOR and of the lamp 18L of signal 18S is interrupted by contact 58 of relay 18APP and by contact 59 of relay 18AP, while the circuit of the 20 180 code transmitter 18CTA is established as contact 61 of relay 18APP and contact 62 of relay 18H are picked up. The contact 180 of code transmitter 18CTA, therefore, is operated to establish and interrupt the circuit of the coding 25 relay 18CTM 180 times a minute. The circuit of the coding relay 18CTM is complete at this time as contact 65 of relay 18H and contact 66 of relay 18AP are picked up. The coding relay 18CTM, therefore, operates to supply master 30 code energy of 180 code frequency to the rails of section 19T.

At this time as the contact 68 of relay 18AP is picked up, the circuit for supplying energy to the operating mechanism 18G of the signal 35 18S is interrupted.

From the foregoing it will be seen that when section 19T is vacant, the relays 18AP and 18APP are energized with the result that the signal 18S is dark, the operating mechanism of the signal is 40 deenergized, and the decoding transformer 18DTA is deenergized.

When a train traveling in the normal direction of traffic, that is from left to right, enters section 19T, it shunts the track relay, not shown, 45 for that section with the result that feed back energy is no longer supplied to the rails of the section and the relay 18AP releases. Release of contact 54 of this relay establishes the circuit for supplying alternating current energy to the track transformer 19TT so that coded cab signal energy is thereafter supplied from any suitable 50 source of alternating current, the terminals of which are designated BX and CX, to the rails of section 19T to operate the cab signal equipment on the locomotive of the train which has entered this section. The alternating current energy supplied to the rails of section 19T is coded at the rate determined by the coding relay 18CTM, and this relay is operating at this time to provide 55 the 180 code frequency so that the cab signal equipment will be conditioned to display its clear indication.

In addition, on release of relay 18AP, contact 68 60 interrupts the circuit of relay 18APP and establishes the circuit for supplying energy to the signal mechanism 18G. The relay 18APP is slow releasing and its contacts remain picked up for a substantial time interval after release of relay 18AP. Accordingly, on release of the 65 relay 18AP the circuit for supplying energy to the primary winding of the transformer 18DTA is established. This circuit is traced from terminal B of a local source of direct current, not shown, through front contact 58 of relay 18APP, 70 back contact 56 of relay 18AP, and front contact 75

78 of relay 18H to contact 71 of the track relay 18TR which alternately establishes connection with the two end terminals of the transformer primary winding, while the center terminal of this winding is connected to terminal C of the 5 source of current.

As soon as the circuit for supplying energy to the transformer 18DTA is completed, energy is induced in the transformer secondary winding and is supplied therefrom through the resonant 10 rectifier unit 18RUA to pick up the relay 18J. Picking up of the contacts 73 and 74 of relay 18J changes the polarity of the energy supplied to the signal mechanism 18G to cause it to condition the signal to display its green or clear indication. The circuit for energizing the mechanism 18G is traced from terminal B through back contact 15 68 of relay 18AP, front contact 76 of relay 18H, front contact 73 of relay 18J, signal mechanism 18G, and front contact 74 of relay 18J to 20 terminal C.

On expiration of a short time interval after release of relay 18AP the relay 18APP releases. This time interval is long enough to permit the relay 18J to pick up and to permit the mechanism of signal 18G to position itself before relay 18APP releases. 25

On release of relay 18APP, contact 58 interrupts the circuit traced above for energizing the transformer 18DTA, and establishes the circuit 30 of the lightout relay 18LOR and the lamp 18L. This circuit includes back contact 58 of relay 18APP and back contact 59 of relay 18AP.

If the lamp 18L is in good condition and becomes lighted, the lightout relay 18LOR will be 35 energized and its contact 77 will pick up and establish a circuit to supply energy to the transformer 18DTA so that energy continues to be supplied to the relay 18J. There is a short interruption in the supply of energy to the transformer 40 18DTA from the time at which relay 18APP releases and the time at which relay 18LOR picks up. The relay 18J is slow releasing, however, and remains picked up during this time interval.

In addition, on release of relay 18APP, contact 45 61 interrupts the circuit traced above for energizing the code transmitter 18CTA, but on picking up of the relay 18LOR its contact 79 establishes a circuit to energize the code transmitter 18CTA so that the code transmitter continues to 50 operate.

Release of contact 66 of relay 18AP interrupts the circuit traced above for energizing the coding relay 18CTM, but another circuit for energizing this relay with energy of 180 code frequency is 55 established on picking up of the relay 18LOR so that energy of 180 code frequency continues to be supplied to the coding relay 18CTM and this relay continues to supply energy of 180 code frequency to the rails of the section in the rear. 60 The circuit for supplying energy to the relay 18CTM is traced from terminal B through contact 180 of code transmitter 18CTA, front contact 81 of relay 18LOR, front contact 88 of relay 18H and back contact 66 of relay 18AP to the 65 relay 18CTM.

From the foregoing it will be seen that when a train enters section 19T, the relays 18AP and 18APP become released and establish the circuit 70 of the transformer 18DTA so that the relay 18J is energized, while energy is supplied to the signal mechanism 18G to condition the signal to display its clear indication. In addition, alternating current energy is supplied to the rails of section 19T to operate the cab signal apparatus on the 75

locomotive to provide a clear cab signal, while energy is supplied to the lamp 18L of the signal 18S to light the lamp and cause the signal to display its clear indication.

5 When the train advances into section 18T, the track relay 18TR is shunted and energy is no longer supplied through the transformers 18DT and 18DTA to the relays 18H and 18J and these relays release. Release of contact 76 of relay 18H 10 interrupts the circuit for energizing the signal mechanism 18G, and this mechanism thereupon conditions the signal 18S to display its red or stop indication.

On shunting of the track relay 18TR energy is 15 no longer supplied to the impulse relay 18IR and this relay no longer supplies impulses of feed back energy to the rails of section 18T. Accordingly, the relays 17AP and 17APP become released and condition the signal 17S to display its clear 20 indication, while alternating current cab signal control energy is supplied to the rails of section 18T.

In addition, on shunting of the track relay 18TR and release of the relay 18H a circuit is 25 established to energize the code transmitter 18CTB which provides impulses of energy of 75 code frequency. The circuit of this code transmitter is traced from terminal B through back contact 61 of relay 18APP, back contact 30 80 of relay 18H, and front contact 85 of relay 18LOR to the code transmitter 18CTB. The contact 75 of the transmitter 18CTB is operated, therefore, to supply energy of 75 code frequency to the coding relay 18CTM over the circuit which 35 is traced from terminal B through contact 75, front contact 87 of relay 18LOR, back contact 88 of relay 18H, and back contact 66 of relay 18AP. The coding relay 18CTM, therefore, operates to 40 supply impulses of master code energy of the 75 code frequency to the rails of section 19T, and when the train vacates section 19T, these 45 impulses of master code energy feed to the track relay for section 19T, while the impulse relay associated therewith then operates to supply impulses of feed back energy to the section rails as previously explained in connection with section 18T.

The impulses of feed back energy supplied to section 19T cause the relay 18AP to pick up and 50 its contact 68 establishes the circuit to supply energy to the relay 18APP to pick it up, while contact 68 interrupts the circuit of the signal mechanism 18G.

On picking up of relay 18AP, contact 54 55 interrupts the supply of alternating current cab signal control energy to the rails of section 19T, while contact 66 interrupts the previously traced circuit for supplying energy of 75 code frequency to the coding relay 18CTM and establishes another circuit for supplying energy thereto. This 60 circuit is traced from contact 75 through back contact 65 of relay 18H and front contact 66 of relay 18AP.

On picking up of relay 18AP, contact 59 65 interrupts the circuit of the lamp 18L and of the relay 18LOR so that the lamp is extinguished and the relay 18LOR releases and its contact 85 70 interrupts the circuit for supplying energy to the code transmitter 18CTB. However, on picking up of relay 18APP, its contact 61 establishes a circuit which includes back contact 62 of relay 18H for energizing the code transmitter 18CTB and it continues to operate so that energy of 75 code frequency is supplied to the 75 rails of section 19T to condition the signal for

that section to display its yellow or caution indication on entrance of a train into the section in the rear.

As long as any portion of the train is present in section 18T, the track relay 18TR is shunted 5 and relay 18H is released and its contact 76 interrupts the circuit of the signal mechanism 18G so that the signal 18S is conditioned to display its red or stop indication when the lamp 18L is lighted. Accordingly, if while section 18T 10 is occupied a second or following train should enter section 19T and release the relays 18AP and 18APP so that lamp 18L is lighted, the signal 18S will display its red or stop indication.

When the train under consideration, that is 15 the train in section 18T, advances into section 17T, the track relay for that section is shunted and the equipment associated therewith operates in the manner explained in connection with section 18T to supply master code energy of 75 20 code frequency to the rails of section 18T and to condition the signal 17S to display its stop indication when the signal lamp is lighted.

When the train vacates section 18T, coded 25 energy is supplied to the track relay 18TR and energy is supplied through the transformer 18DT to the relay 18H and also to the relay 18IR so that relay 18H picks up, while the relay 18IR supplies impulses of feed back energy to the section rails to produce code following operation of the relay 17AR with resultant energization of the relays 17AP and 17APP.

When the relays 17AP and 17APP are picked up, the circuit of the lamp of the signal 17S is interrupted, while the supply of alternating 35 current cab signal control energy to section 18T is cut off.

When relay 18H picks up, its contact 62 40 interrupts the circuit for energizing the transmitter 18CTB and establishes the circuit for energizing the transmitter 18CTA, assuming that the contact 61 of relay 18APP is picked up, and this transmitter operates to supply energy of 180 code frequency.

In addition, on picking up of the relay 18H 45 its contact 65 interrupts the circuit through which energy of 75 code frequency has been supplied to the coding relay 18CTM and establishes a circuit to supply energy of 180 code frequency thereto. The relay 18CTM, therefore, operates 50 at the higher rate and supplies master code impulses of 180 code frequency to the rails of section 19T.

If at this time a second or following train 55 should enter section 19T and release the relays 18AP and 18APP and establish the circuit of the transformer 18DTA, too little energy would be supplied through the resonant rectifier unit 18RUA to pick up the relay 18J since the track relay 18TR is responding to energy of 75 code 60 frequency. The relay 18J, therefore, would remain released and the polarity of the energy supplied to the signal mechanism 18G would be such as to condition the signal to display its yellow or caution indication when the signal lamp 65 is lighted. The circuit for supplying energy to the mechanism 18G would be complete at this time as contact 68 of relay 18AP is released and contact 76 of relay 18H is picked up.

It will be seen, therefore, that if a second or 70 following train enters section 19T at a time when section 18T is vacant and section 17T is occupied, the signal 18S will be conditioned to display its yellow or caution indication, while master code energy of 180 code frequency will con- 75

ture to be supplied to the rails of section 19T.

When the train under consideration advances far enough to vacate section 17T, the track relay for this section responds to energy of 75

5 code frequency with the result that the energy supplied to section 18T is changed from 75 to 180 code frequency. On this change in the energy supplied to the relay 18TR this relay operates at a more rapid rate and if a train enters section 19T the frequency of the energy supplied from the transformer 18DTA will be such that sufficient energy will be supplied through the resonant unit 18RUA to pick up the relay 18J to thereby condition the signal 18S to display its clear indication.

10 On this change in the code supplied to the relay 18TR energy of 180 code frequency continues to be supplied to the rails of section 19T.

20 *Operation of the equipment shown in Fig. 3 in the event a signal lamp is defective*

The system provided by this modification of the invention is arranged so that if the signal lamp of a signal is defective and does not become lighted when it should, the energy supplied to the section in the rear will be controlled so that the signals in the rear of the one with the defective lamp will display more restrictive indications than they normally would.

25 30 When the track stretch is vacant, energy of 180 code frequency is supplied to the track relay 18TR, and when a train enters section 19T, the relay 18AP releases and interrupts the circuit of the relay 18APP.

35 On release of relay 18APP, the circuit of the transformer 18DTA is interrupted, while a circuit is established to supply energy to the lamp 18L and the relay 18LOR. If the lamp is defective, no energy will flow in this circuit and the relay 18LOR will remain released, while its contact 77 will not establish the circuit to supply energy to the transformer 18DTA. Accordingly, energy will not be supplied to the relay 18J and the polarity of the energy supplied to the signal 40 mechanism 18G will be such as to condition the signal to display its yellow or caution indication instead of its clear indication.

45 The equipment is also arranged so that at this time operation of the code transmitter 18CTA is discontinued, while operation of the code transmitter 18CTB is initiated. On release of contact 61 of relay 18APP the circuit of the code transmitter 18CTA is interrupted, while a circuit including back contact 61 of relay 18APP, front 50 contact 80 of relay 18H, and back contact 79 of relay 18LOR is established to energize the code transmitter 18CTB to cause it to operate and provide 75 code for the coding relay 18CTM.

55 From the foregoing it will be seen that on entrance of a train into section 19T at a time when the track stretch is otherwise vacant and when the lamp of the signal 18S is defective, the energy supplied to the coding relay 18CTM is changed from 180 code frequency to 75 code frequency with the result that energy of 75 code frequency is supplied to the rails of section 19T. Accordingly, the cab signal equipment on the locomotive of the train in section 19T will be conditioned to display its caution indication instead of its clear indication and the engineer 60 will reduce the speed of the train so as to be prepared to stop when he reaches signal 18S.

65 In addition, at this time the signal 18S is conditioned to display its yellow or caution indication, if the signal lamp were lighted, so that

any light reflected through the optical system of the signal will be yellow which will be consistent with the indication displayed by the locomotive cab signal apparatus.

70 When the train enters section 18T, the track relay 18TR is shunted and relay 18H becomes released and its contact 76 interrupts the circuit of the signal mechanism 18G and the mechanism conditions the signal 18S to display its stop indication provided the signal lamp were lighted.

75 On release of relay 18H contact 88 interrupts the circuit traced above for supplying energy of 75 code frequency to the coding relay 18CTM, while contact 80 of relay 18H interrupts the circuit for supplying energy to the code transmitter 18CTB. As a result, therefore, energy is not supplied to the coding relay 18CTM and this relay does not operate to supply coded energy to the rails of section 19T. The track relay for section 19T, therefore, will remain released after the train vacates section 19T, while no impulses of feed back energy will be supplied to the section rails and the relays 18AP and 18APP will remain released.

80 When the train under consideration entered section 19T, the track relay for that section was shunted and the equipment associated therewith operated as heretofore described in connection with section 18T to supply energy of 75 code frequency to the section in the rear. Accordingly, when the train vacates section 19T the track relay 18TR continues to be released as master code energy is not supplied to the section rails, and energy of 75 code frequency continues to be supplied to the rails of the adjacent section in 85 the rear of section 19T.

85 If, therefore, a second or following train should enter the section in the rear of section 19T at a time when section 19T is vacant and section 18T is occupied and the lamp of signal 18S is defective, the train will receive a caution indication from the wayside signal at the entrance to the section in the rear of section 19T, while the locomotive cab signal apparatus will also operate to provide its caution indication.

90 When the second or following train advances into section 19T at a time when section 19T is vacant and section 18T is occupied, the cab signal equipment on the locomotive of the train will operate to give its stop or most restrictive indication since at this time the coding relay 18CTM is not operating to supply coded energy to the rails of section 19T.

95 At this time as section 18T is assumed to be occupied, the relay 18H is released and its contact 76 interrupts the circuit of the signal mechanism 18G with the result that the signal 18S is conditioned to display its red or stop indication, if the signal lamp were lighted, and any light reflected through the optical system of the signal will be red, which is consistent with the signal displayed by the cab signal equipment of a locomotive in section 19T.

100 In like manner, if a second or following train should enter section 19T after the first train has vacated section 18T and occupies section 19T, the second train will receive a caution cab signal, while the signal 18S will be conditioned so that yellow light will be reflected therefrom.

105 When the first train occupies section 19T, the equipment associated with that section operates as heretofore explained to supply master code energy of 75 code frequency to the rails of section 19T, and the track relay 18TR responds to

this energy so that energy is supplied through the transformer 18DT to the relay 18H.

- On picking up of relay 18H contact 80 establishes a circuit to supply energy to the code transmitter 18CTB, while contact 88 of relay 18H establishes a circuit to supply energy from the code transmitter 18CTB to the coding relay 18CTM. The circuit for energizing the transmitter 18CTB is traced from terminal B over back contact 61 of relay 18APP, front contact 80 of relay 18H, and back contact 79 of relay 18LOR, while the circuit for supplying energy to the coding relay 18CTM is traced from terminal B over contact 75 of the code transmitter 18CTB, back contact 81 of relay 18LOR, front contact of relay 18H, and back contact 66 of relay 18AP.

As a result of the supply of energy to the coding relay 18CTM this relay supplies master code energy of 75 code frequency to the rails of section 19T, and if at this time the section is vacant, the track relay will respond to this coded energy, while feed back energy will be supplied over the section rails so that the relays 18AP and 18APP become picked up.

- On picking up of relay 18APP contact 61 interrupts the circuit traced above for energizing the code transmitter 18CTB and establishes a circuit including front contact 62 of relay 18H for energizing the code transmitter 18CTA. In addition, on picking up of relay 18AP contact 66 interrupts the circuit traced above for supplying energy of 75 code frequency to the coding relay 18CTM and establishes a circuit including front contact 65 of relay 18H for supplying energy of 180 code frequency to the coding relay 18CTM so that the energy supplied to section 19T is changed from 75 to 180 code, and the signal for section 19T will display its clear indication when the section in the rear thereof becomes occupied. This is proper as the sections 18T and 19T are assumed to be vacant.

If at this time a second or following train enters section 19T, the supply of feed back energy over the rails of this section will be cut off and the relays 18AP and 18APP will become released to thereby discontinue the supply of energy of 180 code frequency to the relay 18CTM, and to supply energy of 75 code frequency thereto so that energy of 75 code frequency will be supplied to the rails of section 19T to condition the locomotive cab signal apparatus to display its yellow or caution indication.

- On release of relay 18AP contact 68 establishes the circuit including front contact 76 of relay 18H for supplying energy to the signal mechanism 18G, and as the contacts of the relay 18J are released, the polarity of the energy supplied to the mechanism 18G is such that the signal will be conditioned to display its yellow or caution indication if the signal lamp were lighted. Accordingly, any light reflected through the optical system of the signal will be consistent with the aspect displayed by the locomotive cab signal apparatus.

From the foregoing it will be seen that the modification shown in Fig. 3 is arranged so that if the signal lamp is defective, the supply of energy of 180 code frequency to the adjacent section in the rear will be cut off as soon as a train enters the section in the rear of the signal and energy of 75 code frequency will be supplied instead so that the cab signal equipment on the locomotive of the train will display its caution indication and the train will approach the defective signal at reduced speed.

In addition, it will be seen that the system is arranged so that when a signal is defective and a train passes through the track stretch, the supply of energy to the rails of the section in the rear of the section with the defective signal is cut off so that the signal for the section in the rear of the defective signal will continue to display its stop indication after the section is vacated and as long as the section with the defective signal is occupied. This insures that as long as the section with the defective signal is occupied that the signal for the section next in the rear will display its stop indication.

As there is in the rear of an occupied section one properly functioning signal which is conditioned to display its stop indication, following trains will be given ample warning of the presence of the first train and will be prepared to stop before reaching the first train.

In addition, it will be seen that the system is arranged so that the mechanism of a signal with a defective lamp is conditioned to cause light reflected through the optical system of the signal to give an indication which is consistent with that given by the cab signal equipment on the locomotive of the train approaching the signal.

Although I have herein shown and described only three forms of railway signaling apparatus embodying my invention, it is understood that various changes and modifications may be made therein within the scope of the appended claims without departing from the spirit and scope of my invention.

Having thus described my invention, what I claim is:

1. In a coded railway signaling system, in combination, a stretch of railway track having a pair of track rails divided by insulated joints into a plurality of successive track sections including a forward and a rearward section, means for supplying coded energy to the rails of said forward section, a track relay receiving energy over the rails of said forward section, a signal governing traffic in said forward section, said signal including a lamp, means responsive to code following operation of said forward section track relay and controlling the circuit of said signal lamp and also controlling the supply of coded energy to the rails of said rearward section, means responsive to flow of energy in the circuit of said lamp for also controlling the supply of coded energy to the rails of said rearward section, and traffic governing means responsive to the flow of coded energy in the rails of said rearward section.

2. In a coded railway signaling system, in combination, a stretch of railway track having a pair of track rails divided by insulated joints into a plurality of successive track sections including a forward and a rearward section, a signal governing traffic in said section, said signal including a lamp, means for supplying coded energy to the rails of said forward section, a track relay receiving energy over the rails of said forward section, an auxiliary relay associated with said track relay, means operative when and only when said track relay is responding to coded energy to energize the auxiliary relay, said auxiliary relay being operative when released to establish a circuit to supply energy to said signal lamp, means responsive to flow of current in the circuit of said lamp for supplying coded energy to the rails of said rearward section, and traffic governing means responsive to the flow of coded energy in the rails of said rearward section.

3. In a coded railway signaling system, in com-

- bination, a stretch of railroad track having a pair of track rails divided by insulated joints into a plurality of successive track sections including adjoining forward and rearward sections, a signal governing movement of traffic in said forward section, said signal including a lamp, a track circuit for the forward section comprising means for supplying energy to the track rails at the exit end of the section and a track relay 5 receiving energy from the section rails at the entrance end of the section, means controlled by said track relay and operative when said relay is deenergized to establish a circuit to supply energy to said signal lamp, means responsive 10 to the flow of energy in the circuit of said lamp and controlling the supply of coded energy to the rails of said rearward section, and indication means responsive to the flow of coded energy in the rails of said rearward section.
- 15 4. In a coded railway signaling system, in combination, a stretch of railway track having a pair of track rails divided by insulated joints into a plurality of successive track sections including a forward and a rearward section, a signal for said forward section having a plurality of lamps for 20 indicating different degrees of traffic restriction and including a first lamp providing a clear indication, a second lamp providing a caution indication and a third lamp providing a stop indication, indication means selectively responsive 25 to the flow of different types of coded energy in the rails of the rearward section, means governed by traffic conditions in said forward section and in the adjoining section in advance for establishing circuits to light the first or the second lamp of said signal and to supply to the rails of the rearward section energy of a character effective to condition said indication means to display its least restrictive aspect, means responsive to flow of current in the circuit of the first 30 lamp and operative on failure of flow of current therein to establish a circuit to light the second lamp, means responsive to the flow of current in the circuit of the second lamp and operative on failure of flow of current therein to establish a 35 circuit to light the third lamp and to change the coded energy supplied to the rails of the section in the rear to a character effective to condition said indication means to display a restrictive aspect, means governed by traffic conditions in 40 said forward section for establishing a circuit to also light said third lamp of said signal and to also supply to the rails of the rearward section coded energy of a character effective to condition said indication means to display said restrictive indication, and means responsive to the flow of current in the circuit of the third lamp and operative on failure of flow of current therein to change the energy supplied to the rails of the section in the rear to a character effective to 45 condition said indication means to display its most restrictive indication.
- 45 5. In a coded railway signaling system, in combination, a stretch of railway track having a pair of track rails divided by insulated joints into a plurality of successive track sections including a forward and a rearward section, a signal for indicating occupancy of said forward section, said signal including a lamp, a track circuit for the forward section comprising means for supplying 50 energy to the section rails at the exit end of the section and a track relay receiving energy from the section rails adjacent the entrance end thereof, means operative when said track relay is deenergized to establish the circuit of said signal lamp, a lightout relay connected in series with said signal lamp, means governed by said lightout relay and operative only when said relay is 55 picked up to supply coded energy to the rails of said rearward section, and traffic governing means responsive only to the flow of coded energy in the rails of said rearward section to provide a proceed indication, whereby said means will operate to provide a proceed indication when the forward section is occupied only if said signal lamp is lighted.
- 60 6. In a coded railway signaling system, in combination, a stretch of railway track having a pair of track rails divided by insulated joints into a plurality of successive track sections including a forward and a rearward section, a signal for indicating occupancy of said forward section, said signal including a lamp, a track circuit for the forward section comprising means for supplying coded energy to the section rails at the entrance 65 end of the section and a code following track

relay receiving energy from the section rails adjacent the exit end of the section, an auxiliary relay associated with said code following track relay, means operative when and only when said track relay is responding to coded energy to energize said auxiliary relay, a circuit complete when said auxiliary relay is released to supply energy to said signal lamp, a lightout relay connected in series with said signal lamp, means operative when said lightout relay is picked up 10 to supply coded energy to the rails of said rearward section, and traffic governing means responsive only to the flow of coded energy in the rails of said rearward section.

7. In a coded railway signaling system, in combination, a stretch of railway track having a pair of track rails divided by insulated joints into a plurality of successive track sections including a forward and a rearward section, a signal for said forward section having a plurality of lamps for 20 indicating different degrees of traffic restriction and including a first lamp providing a clear indication, a second lamp providing a caution indication and a third lamp providing a stop indication, indication means selectively responsive 25 to the flow of different types of coded energy in the rails of the rearward section, means governed by traffic conditions in said forward section and in the adjoining section in advance for establishing circuits to light the first or the second lamp of said signal and to supply to the rails of the rearward section energy of a character effective to condition said indication means to display its least restrictive aspect, means responsive to 30 flow of current in the circuit of the first lamp and operative on failure of flow of current therein to establish a circuit to light the second lamp, means responsive to the flow of current in the circuit of the second lamp and operative on failure of flow of current therein to establish a 35 circuit to light the third lamp and to change the coded energy supplied to the rails of the section in the rear to a character effective to condition said indication means to display a restrictive aspect, means governed by traffic conditions in 40 said forward section for establishing a circuit to also light said third lamp of said signal and to also supply to the rails of the rearward section coded energy of a character effective to condition said indication means to display said restrictive indication, and means responsive to the flow of current in the circuit of the third lamp and operative on failure of flow of current therein to change the energy supplied to the rails of the section in the rear to a character effective to 45 condition said indication means to display its most restrictive indication.

8. In a coded railway signaling system, in combination, a stretch of railway track having a pair of track rails divided by insulated joints into a plurality of successive track sections including a forward and a rearward section, a signal for said forward section having a plurality of lamps and including a first lamp providing a clear indication, a second lamp providing a caution indication and a third lamp providing a stop indication, indication means responsive to flow of coded energy of a first character in the rails of the rearward section to provide a clear indication and to flow of coded energy of a second character to 70 provide a caution indication, means governed by traffic conditions in said forward section and in the adjoining section in advance for establishing circuits to light the first or the second lamp of said signal and to establish a circuit to supply 75

5 coded energy of said first character to the rails of said rearward section, means responsive to flow of current in the circuit of the first lamp and operative on failure of flow of current in said circuit to establish a circuit to light the second lamp, means responsive to the flow of energy in the circuit of the second lamp and operative on failure of flow of current in said circuit to establish a circuit to light the third lamp and
 10 to change the energy supplied to the section in the rear from coded energy of the first character to coded energy of the second character, means responsive to traffic conditions in said forward section for establishing a circuit to light the third lamp and to establish a circuit to supply coded energy of said second character to the rails of said rearward section, and means responsive to flow of current in the circuit of said third lamp and operative on failure of flow of current in
 15 said circuit to interrupt the supply of coded energy of said second character to the rails of said rearward section.

9. In a coded railway signaling system, in combination, a stretch of railway track having a pair 25 of track rails divided into a plurality of successive track sections including a forward and a rearward section, a signal for said section having a plurality of lamps and including a first lamp providing a clear indication, a second lamp providing a caution indication, and a third lamp providing a stop indication, indication means responsive to flow of coded current in the rails of said rearward section, said means being operative on flow of coded energy of a first character to 30 provide a clear indication and being operative on flow of coded energy of a second character to provide a caution indication, means operable when said forward section and the adjacent section in advance thereof are both vacant to establish a circuit for the first lamp including in series therewith a first lightout relay and to also establish a circuit for supplying coded energy of said first character to the rails of said rearward section, means operable when said forward section and the adjacent section in 35 advance are both vacant and the first lightout relay is released to establish a circuit for the second lamp of said signal, means operable when said forward section is vacant and the adjacent section in advance thereof is occupied to establish a circuit for said second lamp of said signal including in series therewith a second lightout relay and to also establish a circuit including a front contact of said second lightout relay for supplying coded energy of said first character to the rails of said rearward section, means operable when said forward section is occupied and the second lightout relay is released to establish a circuit for the third lamp of said signal and to also establish a circuit to supply coded energy of said second character to the rails of said rearward section, means operable when said forward section is occupied to establish a circuit for the third lamp of said signal including in series therewith a third lightout relay and to also establish a circuit including a front contact of said third lightout relay for supplying coded energy of said second character to the rails of said rearward section.

10. In a coded railway signaling system, in combination, a stretch of railway track having a pair of track rails divided by insulated joints into a plurality of successive track sections including a first, a second and a third section, a signal for 75 the second section having a lamp and having mechanism for conditioning the signal when lighted to display a clear, a caution or a stop indication, means for establishing a circuit for said lamp including in series therewith a lightout relay, indication means responsive to flow of coded current in the rails of said third section, said means being operable on flow of coded energy of a first character to provide a clear indication and being operable on flow of coded energy of a second character to provide a caution indication, means operable when said first and second sections are vacant to cause said mechanism to condition said signal to display its clear indication and to establish a circuit to supply coded energy of said first character to the rails of said third section, means operable when said first section is occupied and said second section is vacant to cause said mechanism to condition the signal to display its caution indication and to establish a circuit including a front contact of said lightout relay for supplying coded energy of said first character to the rails of said third section, means operable when said first section is occupied and said second section is vacant and said lightout relay is released to establish a circuit for supplying coded energy of said second character to the rails of said third section, and means operable when said second section is occupied to cause said mechanism to condition the signal to display its stop indication and to establish a circuit including a front contact of said lightout relay for supplying coded energy of said second character to the rails of said third section, whereby energy effective to produce a proceed indication will not be supplied to the rails of the third section when the second section is occupied and said signal lamp is defective.

11. In a coded railway signaling system, in combination, a stretch of railway track having a pair of track rails divided by insulated joints into a plurality of successive sections including a first, a second and a third section, a signal for the second section having a lamp and having mechanism for conditioning the signal when lighted to display a clear, a caution or a stop indication, an approach relay having a contact closed when said third section is occupied and operable when said contact is closed to establish a circuit for said lamp including in series therewith a lightout relay, indication means responsive to flow of coded current in the rails of said third section, said means being operable on flow of coded energy of a first character to provide a clear indication and being operable on flow of coded energy of a second character to provide a caution indication, means operable when said first and second sections are vacant and the third section is occupied to cause said mechanism to condition said signal to display its clear indication and to establish a circuit to supply coded energy of said first character to the rails of said third section, means operable when said first section is occupied and the second section is vacant and the third section is occupied to cause said mechanism to condition said signal to display its caution indication and to establish a circuit to supply coded energy of said first character to the rails of said third section if the lightout relay is picked up and to supply coded energy of said second character to the rails of said third section if said lightout relay is released, and means operable when the second and third sections are occupied to cause said mechanism to condition said signal to display its 70 75

- stop indication and to establish a circuit to supply coded energy of said second character to the rails of said third section if said lightout relay is picked up and to cut off the supply of coded energy to the rails of said third section if said lightout relay is released.
12. In a coded railway signaling system, in combination, a stretch of railway track having a pair of track rails divided by insulated joints into a plurality of successive track sections, a signal for each section capable of displaying a plurality of different indications including a stop, a caution and a clear indication, each signal including a lamp, each lamp having a lightout relay associated therewith, an energizing circuit for each lightout relay including in series therewith the associated signal lamp, a track relay for each section receiving energy over the rails of such section, each track relay having associated therewith a first decoding means including a first auxiliary relay which is picked up when the track relay is responding to coded energy and a second decoding means including a second auxiliary relay which is picked up when and only when the track relay is responding to energy of the second code frequency, each such first auxiliary relay being operative when released to condition the associated signal to display its stop indication and when picked up to condition the signal to display a proceed indication, each such second auxiliary relay being operative when released provided the associated first auxiliary relay is picked up to condition the associated signal to display its caution indication and being operative when picked up provided the associated first auxiliary relay is also picked up to condition the associated signal to display its clear indication, and means governed by each first auxiliary relay and the associated lightout relay for supplying energy to the rails of the adjacent track section in the rear, each such means being operative when said first auxiliary relay is picked up provided the lightout relay is also picked up to supply coded energy of the second code frequency to the rails of said section and being operative when said first auxiliary relay is picked up and the associated lightout relay is released to supply coded energy of the first code frequency to the rails of said section, said means being also operative when the first auxiliary relay is released to supply coded energy of the first code frequency to the rails of said section.
13. In a coded railway signaling system, in combination, a stretch railway track having a pair of track rails divided by insulated joints into a plurality of successive track sections including a forward and a rearward section, a signal for the forward section including a lamp which becomes lighted to cause the signal to display an indication, a track relay for the forward section receiving energy over the rails of said section, means for at times supplying energy of a first code frequency and at other times supplying energy of a second code frequency to the rails of said forward section, a first decoding means associated with said track relay and including a first auxiliary relay which is picked up when the track relay is responding to coded energy and a second decoding means including a second auxiliary relay which is picked up when the circuit of said decoding means is established and the track relay is responding to energy of the second code frequency, said first auxiliary relay being operative when released to condition the signal when lighted to display a stop indication and to effect the supply of energy of the first code frequency to the rails of said rearward section and being operative when picked up to condition said signal to display a proceed indication and to effect the supply of energy of the second code frequency to the rails of the rearward section, said second auxiliary relay being operative when released provided the first auxiliary relay is picked up to condition the signal to display its caution indication and when picked up provided the first auxiliary relay is also picked up to condition the signal to display its clear indication, indication means for said rearward section responsive to flow of coded energy in the rails of said section, an approach relay which is released when the rearward section is occupied, a slow releasing repeater relay energized when said approach relay is picked up, a lightout relay connected in series with the lamp of the signal for said forward section, a circuit including a front contact of said repeater relay and a back contact of said approach relay for energizing said second decoding means, a circuit including back contacts of said approach relay and said repeater relay for energizing said signal lamp and said lightout relay, and a circuit including a front contact of said lightout relay for also energizing said second decoding means.
14. In a coded railway signaling system, in combination, a stretch of railway track having a pair of track rails divided by insulated joints into a plurality of successive track sections including a forward and a rearward section, means for supplying coded energy to the rails of said forward section, a code following track relay having a winding receiving energy over the rails of said forward section, an auxiliary relay associated with said track relay, means responsive to code following operation of said track relay for supplying energy to said auxiliary relay, a signal governing traffic in said forward section, said signal including a lamp, a lightout relay, a circuit including said lamp in series therewith for energizing said lightout relay, means governed by said auxiliary relay and said lightout relay for supplying coded energy to the rails of said rearward section, said means being operative when said auxiliary relay is picked up provided the lightout relay is also picked up to supply coded energy of a first character to the rails of said rearward section and being operative when said auxiliary relay is picked up and the lightout relay is released to supply coded energy of a second character to the rails of said rearward section, said means being also operative to supply coded energy of said second character to the rails of said rearward section when said auxiliary relay is released, and traffic governing means selectively responsive to the flow of coded energy of said first and second characters in the rails of said rearward section, said means being operative in response to flow of coded energy of the first character to provide a first proceed indication and being operative in response to flow of coded energy of the second character to provide a more restrictive proceed indication.
15. In a coded railway signaling system, in combination, a stretch of railway track having a pair of track rails divided by insulated joints into a plurality of successive track sections including a forward and a rearward section, means for supplying coded energy to the rails of said forward section, a code following track relay having a winding receiving energy over the rails

of said forward section, an auxiliary relay associated with said track relay, means responsive to code following operation of said track relay for supplying energy to said auxiliary relay, a signal 5 governing traffic in said forward section, said signal including a lamp, a lightout relay, a circuit including said lamp in series therewith for energizing said lightout relay, means governed by said auxiliary relay and said lightout relay for 10 supplying coded energy to the rails of said rearward section, said means being operative when said auxiliary relay is picked up provided the lightout relay is also picked up to supply coded energy of a first character to the rails of said 15 rearward section and being operative when said auxiliary relay is picked up and the lightout relay is released to supply coded energy of a second character to the rails of said rearward section, said means being also operative to supply 20 coded energy of said second character to the rails of said rearward section when said auxiliary relay is released and said lightout relay is picked up and being operative to prevent the supply of coded energy of either character to the rails of 25 said rearward section when said auxiliary relay and lightout relay are both released, and traffic governing means selectively responsive to the flow of coded energy in the rails of said rearward section, said means being operative in response 30 to flow of coded energy of the first character to provide a first proceed indication and being operative in response to flow of coded energy of the second character to provide a restrictive proceed indication and being operative in response

to the absence of flow of coded energy to provide the most restrictive indication.

16. In a coded railway signaling system, in combination, a stretch of railway track having a pair of track rails divided by insulated joints 5 into a plurality of successive track sections including a forward and a rearward section, means for supplying coded energy to the rails of said forward section, a code following track relay having a winding receiving energy over the rails 10 of said forward section, an auxiliary relay associated with said track relay, means responsive to code following operation of said track relay for supplying energy to said auxiliary relay, a signal governing traffic in said forward section, 15 said signal including a lamp, a lightout relay, an approach relay governed by traffic conditions in said rearward section, said approach relay being energized when said rearward section is vacant and being effective when deenergized to establish 20 a circuit including said lamp and said lightout relay in series, a circuit including front contacts of the approach relay and of the auxiliary relay for supplying coded energy to the rails of the rearward section when the approach relay is en- 25 ergized provided the auxiliary relay is also energized, and a circuit including front contacts of the auxiliary relay and of the lightout relay for also supplying coded energy to the rails of the rearward section when the approach relay is re- 30 leased provided the auxiliary relay and the lightout relay are both energized.

RALPH R. KEMMERER.
